UNITED STATES PATENT OFFICE

130,795

DESIGN FOR A CORNER SEAT

James F. Eppenstein, Chicago, Ill.

Application August 23, 1941, Serial No. 103,003

Term of patent 7 years

To all whom it may concern:

Be it known that I, James F. Eppenstein, a citizen of the United States, residing at Chicago, in the county of Cook and State of Illinois, have invented a new, original, and ornamental Design for Corner Seats, of which the following is a specification, reference being had to the accompanying drawing, forming part thereof, wherein:

Figure 1 is a perspective view of a corner seat, showing my new design; Fig. 2 is a top plan view; and Fig. 3 is a side elevational view thereof.

I claim:

The ornamental design for a corner seat, substantially as shown.

JAMES F. EPPENSTEIN.
